CLAIM

The ornamental design for a wheel front face, as shown and described.

DESCRIPTION

FIG. 1 is a perspective view of a wheel front face in accordance with the present invention.

FIG. 2 is a front view of the wheel front face of FIG. 1; and, FIG. 3 is a side view of the wheel front face of FIG. 1.

The surface shadings are for illustrative purposes only, and form no part of the claimed design. The broken lines represent portions of the wheel and form no part of the claimed design.
